UNITED STATES PATENT OFFICE.

CLARENCE M. EVELETH, OF RIVER FOREST, ILLINOIS.

OIL CAN.

Application filed June 6, 1927. Serial No. 196,756.

This invention relates to a guard or protecting cover to be used in connection with oil cans, to the end that an oil can may be kept clean at all times, eliminating any possibility of the person using the oil can getting his hands dirty from the can.

Another object of the invention is to provide a device of this character which when positioned will closely engage the oil can eliminating any possibility of the can rattling within its cover.

A still further object of the invention is to prevent oil which may adhere to the spout of the can after it has been used, from running over the sides of the protector or cover when the can is positioned on its rack after use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a vertical sectional view through a cover or protector showing an oil can as positioned therein.

Figure 2 is a sectional view taken on line 2-2 of Figure 1.

Figure 3 is a bottom plan view of the device showing an oil can positioned therein.

Referring to the drawing in detail, the reference character 5 designates an oil can which is of the usual and well known construction, and with which the protector embodying the essence of this invention, is used.

The protector is constructed to conform to the shape of the body portion of the oil can, the same being provided with depressions adjacent to the upper end of the body 6, the depressions defining bosses 7 adapted to contact with the body portion of the oil can over which the cover is positioned to set up a binding action between the cover and can to insure against movement of the can within the cover or protector.

Depressions indicated at 8 are formed exteriorly of the cover adjacent to the bottom thereof, which depressions define bosses 9

that engage the bottom of the can and act to hold the can within the cover or protector.

As shown by Figure 1, the upper portion 60 of the cover extends inwardly as at 10 where it is provided with an opening to permit the discharge spout 11 of the oil can to extend therethrough. A protecting collar indicated at 12 extends through the opening 65 in the inwardly extended portion 10 and is provided with depressions defining lugs 13 to contact with the discharge spout 11 and hold the collar in position.

At the base of the collar is a disk 14 that 70 fits under the inwardly extended portion 10, the base being provided with enlargements 15 that engage the upper surface of the threaded base 16 of the spout 11 to hold the disk in spaced relation with the threaded portion 16 so that oil passing between the collar 12 and spout 11, may find its way between the enlargements 15 where it may pass downwardly over the threaded member 16 and prevent it from passing from 75 under the cover when the can is being used to eject oil therefrom.

From the foregoing it will be seen that due to the construction shown and described, the oil which may collect at the 80 end of the spout after the can has been used, cannot possibly find its way onto the cover so that the person using the oil can will be insured against dirtying his hands when using the oil can.

In the use of the device, the oil can is merely positioned in the cover or protector, the bosses contacting with the can to hold the can against movement.

Should it be desired to refill the oil can, 85 it is of course necessary to force the oil can from the cover and remove the threaded portion 16 and refill the can in the usual manner.

I claim:

1. A protector for oil cans including a body portion shaped to conform to the shape of the can positioned therein, a collar through which the discharge spout of the can extends, means for providing a space 105 between the collar and discharge spout to allow oil to pass under the protector, and means forming a part of the protector for gripping the can to hold the can within the protector.

2. A protector for oil cans including a body portion shaped to conform to the

100

110

shape of the can positioned in the protector, said protector having an inwardly extended upper portion formed with an opening to receive the discharge spout of the can, a collar extended through the opening and having a disk at its bottom, said disk adapted to contact with the inwardly extended portion, said collar having depressions providing enlargements adapted to contact with the spout to hold the collar in spaced relation with the spout to allow oil to pass therebetween.

3. A protector for oil cans including a body portion adapted to be fitted over a can, said body portion having a removable col-

lar through which the spout of the can passes, said collar being of a diameter to provide a space between the spout and collar, to allow oil to pass therebetween, a disk on one end of the collar, and means forming a part of the disk for holding the disk in spaced relation with the top of the can to allow oil to pass under the disk, and means for holding the can within the protector.

25

In testimony that I claim the foregoing as my own, I have hereto affixed my signature.

CLARENCE M. EVELETH.
